poration of Delaware

Original application July 10, 1939, Serial No.
283,548. Divided and this application August
3, 1940, Serial No. 350,216

3 Claims. (Cl. 179—171.5)

Our invention relates to improvements in systems and apparatus for monitoring and signal-level control.

This application is a division of our copending application, Serial No. 283,548, filed July 10, 1939, Patent No. 2,229,556.

For the purpose of monitoring percent modulation of transmitters, it is customary to employ a cathode-ray tube oscillograph. When it is observed, from the monitor pattern on the fluorescent screen, that the signal-level is too high, manual adjustment of the associated amplifier is made to reduce the output-signal-level and thus prevent over modulation of the transmitter.

One of the objects of our invention is to provide an improved system and apparatus for monitoring and signal-level control whereby over modulation of a transmitter is prevented by automatic adjustment of the associated amplifier.

Other objects and advantages will hereinafter appear.

For the purpose of illustrating our invention, an embodiment thereof is shown in the drawings, wherein

Figure 1 is a simplified, diagrammatic view of a system constructed and operating in accordance with our invention;

Fig. 2 is an enlarged, detail, sectional view, the section being taken on the line 2—2 in Fig. 1; and

Fig. 3 is a view similar to Fig. 1, showing a modification.

The basic principle involved in the disclosed embodiment of our invention resides in the fact that certain substances or materials yield a greater number of electrons of secondary emission when bombarded by primary electrons, than certain other substances. For example, there is a difference between the respective degrees of secondary emission from aluminum and carbon, or from silver and glass, when screens of these materials are bombarded or scanned by a ray or beam of electrons under the same operating conditions.

In Fig. 1, the reference numeral 10 designates generally a monitor device in the form of a cathode-ray tube, comprising an evacuated tube 11 having in the neck portion thereof an electron gun of a conventional construction for developing a ray or beam 12 of electrons directed at and focused on a screen or target 13 at the other end of the tube. The screen 13 comprises a base plate 14 of aluminum foil to which a supporting contact 15 is electrically connected. The

aluminum plate 14 may be backed by a suitable plate to impart sufficient rigidity, as will be well understood. A coating 16 of carbon ink is applied to the central portion of the aluminum surface, as represented in Fig. 2. Upon the coating of carbon ink, fluorescent material is applied to form a rectangular, fluorescent screen 17.

For the purpose of monitoring, a sweep circuit 18 applies a suitable wave to one of the deflecting plates 19, whereby the pattern is spread out in the usual manner for observation and analysis.

The signal to be observed is applied by the connection 20 to one of the deflecting plates 21. In operation, therefore, the deflecting means 18, 19 cause deflection of the electron beam 12 in one sense or direction, and the deflecting means 21 causes deflection of the beam in another sense or direction, whereby the monitor pattern, represented in Fig. 2 by the reference numeral 22, appears on the fluorescent screen 17. As the target or screen structure 13 is scanned by the electron beam 12, a signal is developed which may be taken directly from the target by the output line 23. The monitor device is provided with a collector ring 24 adjacent the target, and from which the signals may be taken by the output connection 25.

The signals taken from the collector ring 24 will be of polarity opposite to that of the signals taken directly from the target itself. Having either polarity available is an advantage.

If the operating action of the monitor device 10 occurs outside of a predetermined range, or to a predetermined extent, the desired control signal will appear in the output line 23. For example, if the beam 12 is deflected by the plates 21 beyond the physical extent of the fluorescent screen 17, such as to either or both of the dash lines 26, the electrons will bombard the coating 16 of carbon ink, and due to the changed amount of secondary emission occurring in such case, a signal of changed intensity will appear in the output line 23.

In Fig. 1, the signal to be monitored is an audio or video signal from a source represented at 26. This signal passes through an amplifier 27 to a modulated stage 28 in which a carrier from a source 29 is modulated. The modulated carrier is transmitted by a suitable transmitter represented at 30.

The signal to be observed, in this case, is the modulated radio-frequency at 31, the latter being supplied from the modulated stage 28 through the connection 32.

The reference numeral 33 designates an automatic signal-changing circuit, which may comprise any suitable and well-known means for changing the signal-level output from the amplifier 27. For example, this means or unit 33 may embody a servomotor which is responsive only to a control signal from a suitable relay 34 supplied through an amplifier 35 from the output line 23 of the monitor device 10.

The arrangement and adjustments in our improved system are such that, as long as modulation of the transmitter 30 is within 100%, the monitor pattern 22 is within the physical extent of the fluorescent screen 17, and in the output line 23 from the monitor device 10 there is no signal which is effective to cause operating action of the relay 34. However, if the monitor pattern goes beyond the edge of the fluorescent screen, under which condition the electrons of the beam 12 will bombard the carbon-ink coating 16, the signal occurring in the output line 23 will be of changed intensity so as to cause operation of the relay 34 and consequent operation of the unit 33 in a step-by-step fashion until the signal-level output of the amplifier 27 is changed to the point whereat the monitor pattern 22 is again within the physical extent of the fluorescent screen 17.

A warning device, represented at 36, and which may be audible or visual, may be controlled from the relay 34 and caused to operate when the unit 33 is caused to function, that is, when modulation of the transmitter 30 approaches or reaches 100%.

Considering one of the broader aspects of our invention, the output connection 23, the amplifier 35, the relay 34, and the level-changing unit 33, may be considered as constituting feed-back connecting means from the monitor device 10 to the amplifier 27.

Although the disclosed embodiment of our invention relates more particularly to a system for automatically preventing over modulation of a transmitter, the invention may be embodied in systems for other purposes. For example, the device 10 may be used in a system wherein the pattern 22 on the fluorescent screen would be a true representation of the heart-beat of a patient, such as in the system disclosed in the Patent 2,221,398, November 12, 1940, to William A. Geohegan. In such case, the arrangement and adjustments might be such that if the heart-beat or pulse exceeds a given value, whereat the pattern 22 goes beyond the physical extent of the fluorescent screen, the resulting control signal in the output line 23 is effective to cause actuation of a relay, such as the relay 34, or actuation of a warning device, such as the device 36. In this way, the required medical apparatus may be automatically controlled to correct for the abnormal pulse, or an audible or visible signal given whereby the attending surgeon is instantly apprised of the patient's abnormal pulse condition.

The principle and operating action in the embodiment of our invention shown in Fig. 3, is the same as that in Figs. 1 and 2. In Fig. 3, the various parts, units and connections, corresponding respectively to those in Figs. 1 and 2, have been designated by the same respective reference numerals, but with the suffix *a*, as those in Figs. 1 and 2. Fig. 3 shows a sound system, in which the amplifier 27a corresponds to the amplifier 27 in Fig. 1, and the associated microphone 26a corresponds to the source 26 in Fig. 1. In operation,

if the output-signal-level of the amplifier 27a exceeds a predetermined value, a control signal appears in the output line 23a from the monitor device 10a, in the same manner and for the same reason as in Figs. 1 and 2. This control signal, as in Fig. 1, is effective to cause actuation of the relay 34a, in step-by-step fashion, until the output-signal-level of the amplifier 27a is changed or restored to the desired operating level.

From the foregoing, it will be seen that in our improved system, the device 10 serves a double purpose, namely, that of a monitor, and that of a selective, overload-relay.

Various modifications, within the conception of those skilled in the art, are possible without departing from the spirit of our invention, or the scope of the claims.

We claim as our invention:

1. In an automatic amplitude control system, a cathode-ray tube having a screen surface comprising a central fluorescent portion having one secondary emission characteristic and adjacent portions having a different secondary emission characteristic, means for causing an electron beam to scan said portions, means for causing said scanning to be controlled by a signal to be monitored, said screen portions being so disposed that overscanning from said central portion to any part of said adjacent portions will produce a change in secondary electron emission, means for developing a control potential in response to said change in secondary electron emission, and means for controlling said first named signal in accordance with said control potential.

2. In an automatic amplitude control system, a cathode-ray tube having a screen surface comprising a central fluorescent portion having one secondary emission characteristic and adjacent portions having a different secondary emission characteristic, means for causing an electron beam to scan said portions, means for causing said scanning to be controlled by a signal to be monitored, said screen portions being so disposed that overscanning from said central portion to any part of said adjacent portions will produce a change in secondary electron emission, means for developing a control potential in response to said change in secondary electron emission, and means for controlling said first named signal in accordance with said control potential, said screen surface providing for visual observance of said first named signal.

3. In an automatic amplitude control system, a cathode-ray tube having a screen surface comprising a central fluorescent portion having one secondary emission characteristic and adjacent portions having a different secondary emission characteristic, means for causing an electron beam to scan said portions, means for causing said scanning to be controlled by a signal to be monitored, said screen portions being so disposed that overscanning from said central portion to any part of said adjacent portions will produce a change in secondary electron emission, means for developing a control potential in response to said change in secondary electron emission, and means for controlling said first named signal in accordance with said control potential, said last named means including relay means controlled from said output circuit and being responsive only to such control signal.
